SHOE LAST

Harvey S. Konheim, New York, N. Y.

Application February 20, 1934, Serial No. 712,103

3 Claims. (Cl. 12—135)

This invention relates to a last and deals more specifically with a separable last.

It is an object of this invention to produce a last having separable forward and rear sections to facilitate the insertion and removal of the last in the shoe.

A further object of this invention is to provide a separable last which is adapted to be inserted in a shoe while in its open position; and after insertion is adapted to be closed gradually, so that it slips into place evenly in the shoe and causes the latter to conform to the last without wrinkling or any undue strain on the shoe.

And it is a further object of this invention to provide a last the length of which from tip of toe to rear of heel is adjustable and changeable as desired.

Another object of this invention is to provide a last having separable sections, one being moveable relatively to the other in such a way, that the motion imparted to cause separation causes, at the same time, a decrease in the effective length of the last.

These and other objects of the invention will be readily apparent to those skilled in the art from the following description taken in connection with the accompanying drawing, in which:

Fig. 1 is a side view of a last embodying the present invention.

Fig. 2 is a longitudinal sectional view through the center of the last, showing the operating mechanism.

Fig. 3 is an assembled view of a screw used in the present last.

Figs. 4-7 relate to detail views of parts of the operating mechanism.

Referring in detail to the drawing, the last 10 is seen to comprise a forward section 11 and a rear section 12. These sections are preferably formed by taking a last of suitable size and shape and cutting it transversely along the lines 14, 15, and 16 as shown in Figs. 1 and 2. The surfaces 14, 15, and 16 are step shaped and are complementary, so that when the sections of the last are together the parts register, but as the sections are separated the surface 14 of one section slides along the surface 14 of the other; the surface 16 of one slides along the surface 16 of the other; while the intermediate surfaces 15 separate from each other remaining in parallel relation, as shown in Figs. 1 and 2. The angle of the parallel cuts along lines 14 and 16 may be varied depending upon the extent to which it is desired that the length of the last be reduced, for a given

separation of the sections 11 and 12. In practice it has been found that if the cuts 14 and 16 be made at an angle of 30-40 degrees with respect to the bottom surface of the forward section, satisfactory results will be obtained. In some cases the angle may be run as high as 45 degrees or higher, and in some cases the angle may be less than 30 degrees.

The sections having been cut as described, the forward section is now taken and a hole 20 is drilled along the median line thereof at an angle parallel to the cuts 14 and 16. The hole 20 is positioned substantially at the centre of the surface formed by the cut along the lines 15. The hole 30 is similarly drilled in the rear section 15 so that when the sections are fitted together the holes 20 and 30 register with each other exactly, forming one continuous hole from the instep portion of the last through to the shank portion 20 thereof. Obviously, the hole 20—30 may be drilled through before the cutting apart of the sections.

Now, the top of the hole 20 is countersunk at 21 to receive a stud 22, which is screwed thereinto. The stud 22 is also internally threaded at 23.

The hole 30 is countersunk at 31 and a bushing 32 is screwed thereinto as shown in Fig. 2. The bushing 32 is screwed into the countersunk portion 31 and seated against the shoulder 33 thereof.

A screw member 40 having a square head 41 and a shank 42 is provided with thread 43 which mesh with the threads of the stud 22. A lug 44 is formed on the head 41 for the purpose more fully explained hereinafter. The end of the screw member is internally threaded to receive a screw 50, and the washer 51 is held against the bottom edge of 40 by means of the screw 50.

The member 40 is now inserted so that the head 41 lies in the hole 30 with the lug 44 abutting 40 against the bottom surface of the bushing 32. A second bushing 60 externally threaded at 61 and provided with the head 62 is now screwed into the countersink 31 until the head 62 abuts against the bottom thereof. The parts are so dimensioned that when the bushing 60 is home its inner end just contacts with the lug 44, thus holding the member 40 in place and yet permitting it to turn freely about its longitudinal axis, the lug 44 riding freely in the space between the bushings 32 and 60.

The sections are now ready to be assembled. The member 40 is screwed into the bushing 22 by means of a suitable key 70 having a handle 71 and a receptacle 72 which fits the square head 41.

Finally the washer 51 is mounted on the end of 40 by means of the screw 50.

The operation is as follows:

The turning of the screw member 40 by the key 70 causes, by the meshing of the threads 43 with the threads 23, the sections to be moved toward or away from each other, for clamping and unclamping said sections, respectively, depending on the direction in which the screw is turned. 5
10 The screw member rides freely in the rear section in fixed relation thereto. In order to prevent actual separation of the sections, or in order to prevent the screw 40 from leaving the bushing 22 in the normal use of the device, the washer 51
15 acts as a stop, permitting the screw member to be unscrewed only a limited amount, which is predetermined according to the amount it is desired to separate the sections in operation.

In the use of the present device the time spent 20 in screwing the sections together or apart by the key 70 becomes in many cases an important factor. It is also within the scope of this invention to provide a suitable mechanical device by means of which it is merely necessary for the user to hold 25 the last in position while the said device turns the screw a predetermined amount and then stops. Devices of this kind are known in the art. For example, such machines are available in the shoe art, specifically for the purpose of driving 30 a screw or drill a certain predetermined distance into a heel while the same is held in place against the machine. By suitable adjustment such devices may be applied to the present invention.

Obviously, many changes in the herein disclosed embodiment of the invention will readily suggest themselves to those skilled in the art, without departing from the spirit and scope of this invention. This invention is therefore not to be limited in scope except as defined in the 40 appended claims.

Having thus described my invention, I claim:

1. A last having a first section, a second section 45 movable relatively thereto, said sections having aligned openings therethrough extending from the top toward the bottom of the last, two apertured members mounted within the opening in said first section and disposed in spaced relation longitudinally of said opening, an internally 50 screw threaded apertured member mounted within the opening in said second section, and a ro-

tatable rod passing through the apertures of all of said members, said rod having a screw-threaded portion in engagement with said internally screw-threaded member and a lug positioned between the two apertured members in said first section whereby rotation of said rod moves said sections with relation to each other to vary the length of the last. 5

2. A last having a first section, a second section movable relatively thereto, said sections having aligned openings therethrough extending from the top toward the bottom of the last, two apertured members mounted within the opening in said first section and disposed in spaced relation longitudinally of said opening, an internally 15 screw threaded apertured member mounted within the opening in said second section, and a rotatable rod passing through the apertures of all of said members, said rod having a screw threaded portion in engagement with said internally screw 20 threaded member and a lug positioned between the two apertured members in said first section whereby rotation of said rod moves said sections with relation to each other to vary the length of the last, said rod and sections being so related 25 that the rotation of the rod in one direction relatively moves said sections away from each other to decrease the length of the last.

3. A last having a first section, a second section movable relatively thereto, said sections having aligned openings therethrough extending from the top toward the bottom of the last, two apertured members mounted within the opening in said first section and disposed in spaced relation longitudinally of said opening, an internally 30 screw threaded apertured member mounted within the opening in said second section, and a rotatable rod passing through the apertures of all of said members, said rod having a screw 35 threaded portion in engagement with said internally screw threaded member and a lug positioned between the two apertured members in said first section whereby rotation of said rod moves said sections with relation to each other to vary the length of the last, and means carried 40 by said rod and adapted to engage said apertured member to limit relative movement of said sections. 45
